PUZZLE PLAQUE

Ernest M. Baber, Jr., Denver, Colo.

Application August 25, 1958, Serial No. 52,378

Term of patent 3½ years

(Cl. D34—15)

FIG. 1

I claim:

The ornamental design for a puzzle plaque, substantially as shown.
